UNITED STATES PATENT OFFICE.

WILLIAM SHAW, HENRY SHAW, AND JOSEPH SHAW, OF JACKSONVILLE,
FLORIDA.

SKYLIGHT FOR PHOTOGRAPHIC GALLERIES.

SPECIFICATION forming part of Letters Patent No. 517,364, dated March 27, 1894.

Application filed June 14, 1893. Serial No. 477,597. (No model.)

To all whom it may concern:

Be it known that we, WILLIAM SHAW, HENRY SHAW, and JOSEPH SHAW, citizens of the United States, residing at Jacksonville, 5 in the county of Duval and State of Florida, have invented a new and useful Photogra-
pher's Sun-Shade, of which the following is a specification.

Our invention relates to improvements in 10 lights for operating rooms of photographic galleries, and the objects in view are to pro-
vide means for softening and toning down the
sunlight that enters the room; to avoid the
necessity of employing for such purposes nu-
merous curtains or shades.

Heretofore it has been customary to em-
ploy under the glass roof numerous curtains
or shades which necessitated as many or more
strings for operating the same, and disad-
vantages have arisen from the fact that the
shades would wear, become torn, the strings
broken, &c.

For our invention, however, we propose to
avoid the employment of these shades, and,
25 as before stated, soften the light through other
means.

Referring to the drawings—Figure 1 is a
perspective view of a roof, the same being
provided with our invention. Fig. 2 is a ver-
30 tical transverse sectional view of the device.

Like numerals of reference indicate like
parts in all the figures of the drawings.

The roof 1 is provided with the usual sky-
light opening 2 having a plain glass panel 3.
35 The roof, in the present instance, is of the
gable style, that is, slanting, and the upper
and opposite sides of the opening are sur-
rounded by walls 4 and 5, respectively. Each
wall consists of a metal or other sash, 6, the

said sash when formed of metal being pref- 40
erably U-shaped in cross section. In the sash
there is slid a series of ground glass panels 7,
the whole constituting the wall.

It will be seen that if at any time any one 45
or more of the panels should become broken
it may be replaced by another panel of simi-
lar kind. For instance, if one of the middle
panels should become broken it may be re-
moved and the other slid together after which
a new panel may be placed in the end of the 50
sash.

A skylight thus provided, it will be seen, is
protected at certain times during the day from
the direct rays of the sun which can only come
through the ground glass before passing 55
through the plain panel of the skylight and
gaining access to the operating room, thus
avoiding the necessity of employing numerous
curtains and other necessary accessories.

Having described our invention, what we 60
claim is—

The combination with the transparent sky-
light of a photographic room, of a series of
sashes arranged around or partially around
the same, and provided with upper and lower 65
parallel ways, and a series of independent
ground-glass panels removably arranged in
said ways for the purpose described, substan-
tially as specified.

In testimony that we claim the foregoing as 70
our own we have hereto affixed our signatures
in the presence of two witnesses.

WILLIAM SHAW.

HENRY SHAW.

JOSEPH SHAW.
